FLUID-CUSHIONED ARTIFICIAL LEG

John Haller, Northville, Mich.

Application June 21, 1952, Serial No. 294,821

8 Claims. (Cl. 3—1.2)

1

This invention relates to artificial limbs and, in particular, to artificial legs.

One object of this invention is to provide a fluid-cushioned artificial leg enabling the wearer to obtain a smooth and even heel and toe action of the foot together with a desired amount of resistance to such action, this resistance being adjustable to provide a stiff action for a heavy person or a light action for a lightweight person.

Another object is to provide a fluid-cushioned artificial leg of the foregoing character, wherein the cushioning action is brought about by the reciprocation of a piston within the ankle portion of the artificial leg in response to the rocking of the foot portion, the flow of fluid resulting from the reciprocation of the piston being controlled by an adjustable resistance member, such as a spring-pressed valve which yieldingly opposes the free flow of such fluid with a predetermined resistance.

Another object is to provide a fluid-cushioned artificial leg of the foregoing character wherein the reciprocating piston is also yieldingly opposed, as by a compression spring which returns the piston to its starting point when the foot rocks back to its neutral position between the extreme forward and rearward portions of the stride.

Other objects and advantages of the invention will become apparent during the course of the following description of the accompanying drawings, wherein:

Figure 1 is a side elevation, mainly in central vertical section, of the lower portion of a fluid-cushioned artificial leg in its neutral position according to one form of the invention;

Figure 2 is a horizontal section taken along the line 2—2 in Figure 1;

Figure 3 is a view similar to Figure 1, but showing the positions of the parts when the foot is at the forward end of its forward stride; and

Figure 4 is an enlarged fragmentary view of one of the ball check valves of Figure 1, showing the bypass grooves therein.

Referring to the drawings in detail, Figure 1 shows a fluid-cushioned artificial leg, generally designated 10, the upper portion being of conventional construction, particularly as regards its means of attachment to the stump of the living leg remaining after amputation. The artificial leg 10 is provided with a fluid-operated cushioning device, generally designated 11, mounted in the ankle portion 12 of the leg 10 to which the foot portion, generally designated 13, is pivoted, as at the pivot joint 14.

2

The foot portion 13 is shaped like a human foot, so as to match the wearer's other foot in size and shape, except that a wedge-shaped clearance is provided between the forward and rearward portions or toe and heel portions 15 and 16 by providing wedge-shaped gaps between the upper flat surfaces 17 and 18 of the foot portion 13 and the lower flat surfaces 19 and 20 of the ankle portion 12. The portions 17 and 18 are inclined at an obtuse angle to one another as are the ankle portions 19 and 20, in order to provide these wedge-shaped clearance spaces 21 and 22 facilitating normal striding or walking motion by permitting rocking of the foot portion 13 relatively to the ankle portion 12 around the pivot joint 14.

The pivot joint 14 consists of a pair of aligned vertical bores 25 and 26 in the foot and ankle portions 13 and 12 respectively, these receiving ball and socket bolts 27 and 28 respectively. The ball bolt 27 is anchored in position by a nut 29 mounted in a countersink 30 and provided with wrench or spanner holes 31 by which its threaded bore 32 is threaded upon the threaded portion 33 of the bolt 27. The upper end of the bore 25 terminates in a spherical clearance recess 35 above which the ball head 36 of the ball bolt 27 projects.

The ball head 36 is provided with a spherical convex surface 37 which is seated in a corresponding spherical concave surface 38 provided in a hollow spherical shell portion 39 on the lower end of the socket bolt 28. The outer surface 40 of the spherical shell 39 has a spherical curvature concentric with the curvature of the surfaces 37, 38 and 35 and closely fitting the spherical surface 35 in the rocking action of the foot portion 13 relatively to the ankle portion 12. The shell portion 39 is seated in a spherical socket 41 in the lower end of the ankle portion 12 whereas the upper end of the socket bolt 28 is threaded as at 42 to receive a retaining nut 43 and passes through a hole 44 in the lower end or head 45 of a fluid cylinder 46.

The upper surfaces 17 and 18 of the foot portion 13 are provided with cup-shaped sockets 50 and 51 respectively receiving hardened metal contact plugs or buttons 52 and 53 respectively located at short distances from the center 54 of the ball head 36. Engaging the contact buttons 52 and 53 are the rounded lower ends 55 and 56 respectively of reciprocable motion-transmitting rods 57 and 58 reciprocably mounted in bores 59 and 60 located with their axes parallel to and spaced equidistantly from the axis of the socket bolt 28. The rods 57 and 58 pass

through holes 61 and 62 in the cylinder head 45 aligned with the bores 59 and 60.

The fluid cylinder 46 is mounted in a cylindrical socket or bore 65 opening into a hollow 66 within the upper part of the ankle portion 12, and is provided with an outer cylinder bore 67, the upper end of which is threaded as at 68 and closed by a threaded plug or head 69 threaded therein as at 70 and provided with wrench or spanner sockets 71. On its underside, the head 69 is provided with a cylindrical recess 72 receiving a spring abutment collar 73 of similar configuration and having a central bore 74 opening into a counterbore 75 in its upper end. Passing through the bore 74 and having its upper end seated in a coaxial counter-bore 76 in the cylinder head or plug 69 is a hollow tubular stem 77 having an annular recess 78 near its upper end engaged by a snap ring 79 mounted in the counterbore 75. The spring abutment collar 73 is provided with a reduced diameter portion 80 having a surrounding annular shoulder 81 which serves as an abutment for the upper end of a helical compression spring 82.

The lower end of the compression spring 82 engages an annular abutment shoulder 83 on a closure head 86 which is provided with a threaded portion 87 by which it is threaded into the correspondingly threaded portion 88 at the upper end of an inner cylinder bore 89 within a hollow piston 90 reciprocably mounted within the outer cylinder bore 67. A gasket 91 of yieldable material, such as rubber or synthetic rubber, prevents fluid leakage and provides resilience at this location. The midportion of the tubular stem 77 passes through a bore 92 in the closure head 86 of the hollow piston 90 and emerges within the inner cylinder bore 89 where it is provided with an enlargement 93 having an annular abutment surface 94 beneath which the stem 77 is provided with an extension 95. The closure head 86 of the piston 90 is provided with an annular recess 96 receiving a so-called O-ring 97 of elastic deformable material such as rubber or synthetic rubber and this is held in position by a retaining ring 98 mounted in a recess 99 by means of screws 100.

Mounted on the extension 95 of the hollow or tubular stem 77 is an annular stationary inner piston head 101 with its upper end 102 engaging the abutment shoulder 94 and with its midportion provided with an annular recess 103 also receiving an O-ring 104 of elastic deformable material such as natural or synthetic rubber, in order to prevent fluid leakage between the piston 90 and cylinder 46. The piston head 101 is held in position by a snap ring 105 seated in an annular recess 106 in the lower end of the stem extension 95 and engaging a port ring 107 provided with a plurality of circumferentially-spaced lower fluid ports 108 (one only being shown). The port ring 107 is secured in an annular recess 109 in the lower end of the inner piston head 101 by means of screws 110.

Immediately above the ports 108, the inner piston head 101 is provided with a corresponding number of cylindrical ball valve chambers 111, each of which contains a vertically reciprocable ball check valve member 112. The ball check valve members 112 are movable upward against seats consisting of the lower ends of upper fluid ports 113 which extend from the upper ends of the ball valve chambers 111 into radial half-teardrop-shaped fluid passages 114 leading past the annular abutment surface 94 into the upper end of the inner cylinder bore 75 115 and 117. Meanwhile, the ball check valve

89. The upper ends of the lower fluid ports 108 are prevented from being closed by the balls 112 by the provision of bypass grooves 108a formed therein.

Extending upward through the tubular stem extension 95 from the lower part of the inner cylinder bore 89 is a central fluid passageway 115, the upper end of which serves as a ball valve seat in an enlarged bore 116, the lower portion of which is smooth and the upper portion threaded. Running from the ball chamber 116 radially through the stem enlargement 93 to the upper portion of the inner cylinder bore 89 is a fluid passageway 117. Reciprocably mounted in the lower end of the enlarged bore 116 is a ball check valve member 118 which is urged downwardly by a headed pin 119 which itself is urged downwardly by a helical compression spring 120 mounted in the hollow stem bore 116. The upper end of the spring 120 abuts against the lower end of a screw plug 121 threaded into the threaded upper portion of the bore 116, and adjustable by means of an ordinary screw driver. The upper end of the stem bore 116 is closed by a screw plug 122 threaded into the upper end thereof and having its head seated in a recess 123 in the cylinder head 69. Thus the screw 122 also holds the tubular stem 77 within the counterbore 76. A fluid passageway or bleeder hole 124 extends obliquely upward from the space above the piston head 101 within the stem enlargement 93 into the portion of the stem bore 116 above the spring abutment pin 119 to release fluid leaking past the pin 119.

35. The inner piston head 101 and the stem enlargement 93 are made in two pieces in order to provide convenient machining of the passageways 114. It is possible, however, to form the head 101 integral with the stem enlargement 93 by rendering this machining operation somewhat more complicated.

In the operation of the invention, let it be assumed that the leg 10 is strapped or otherwise attached by conventional means (not shown) to the stump of the amputated leg and is, of course, of sufficient length for that purpose. By previously having removed the sealing plug 122 from the upper end of the bore 116 within the tubular stem 77, the adjusting screw 121 is screwed upward or downward to increase or decrease the force exerted by the helical spring 120 upon the contact pin 119 which engages the ball check valve 118, until the desired resistance is obtained to the flow of fluid upward through the passageway.

55. Let it be assumed that the wearer thrusts his leg forward to begin to walk, placing his weight upon the heel portion 16 of the foot 13. This action (Figure 3) causes the foot 13 to rock about the pivot joint 14, forcing the motion-transmitting rod 58 upward and consequently pushing the hollow piston 90 upward in the cylinder bore 67, toward the stationary inner piston 101, compressing the spring 82. The fluid trapped below the piston head 101 is forced upward through the passageway 115, raising the ball check valve 118 off its seat at the upper end of the passageway 115 and thereby overcoming the thrust of the spring 120 and compressing it (Figure 3). This permits the fluid to pass from the passageway 115 through the passageway 117 into the upper end of the inner cylinder bore 89. As the passageways 115 and 117 are constricted, the action is cushioned by the spurtng of the fluid, such as oil, through these constricted passageways 115 and 117. Meanwhile, the ball check valve

112 has risen, having been forced upward by fluid passing through the passageways 108 into the chamber 111, causing the ball 112 to seal the lower ends of the passageways 113 (Figure 3).

As the foot 13 rocks about the pivot joint 14 during the completion of the stride, the rearward piston rod 58 is pushed downward in response to the pushing downward of the hollow piston 90 by the compression spring 82 and fluid passes from the upper part of the inner bore 89 to the lower part thereof by way of the radial passageways 114 and the passageways 113 and 108 past the ball valves 112. After the foot passes the neutral or mid-stride position (Figure 1), the rod 57 is pushed upward, again pushing the hollow piston 90 upward and compressing the spring 82 while again forcing the ball check valve 118 off its seat in compressing its spring 120, again releasing fluid to pass through the passageways 115 and 117 into the upper part of the inner cylinder bore 89 in the same manner as described in connection with Figure 3. This again exerts a cushioning action in the same way as described above. When the walker reaches the rearward end of his stride and starts forward again, the foot 13 again rocks through the neutral position of Figure 1 to the forward position of Figure 3, repeating the foregoing operations.

What I claim is:

1. A fluid-cushioned artificial leg comprising a leg member, a foot member pivotally attached to said leg member for rocking motion relatively thereto, a fluid cylinder mounted in one of said members and having an outer cylinder bore therein, a hollow movable piston reciprocably mounted in said outer cylinder bore and having an inner cylinder bore therein, a stationary piston fixedly mounted in said inner cylinder bore, said stationary piston having a restricted forward fluid passageway and a return fluid passageway therethrough, and a motion-transmitting element extending from said foot member through said cylinder to said movable piston and responsive to the rocking of said foot member for reciprocating said movable piston in said cylinder.

2. A fluid-cushioned artificial leg comprising a leg member, a foot member pivotally attached to said leg member for rocking motion relatively thereto, a fluid cylinder mounted in one of said members and having an outer cylinder bore therein, a hollow movable piston reciprocably mounted in said outer cylinder bore and having an inner cylinder bore therein, a stationary piston fixedly mounted in said inner cylinder bore, said stationary piston having a forward fluid passageway and a return fluid passageway therethrough, a one-way valve disposed in one of said passageways permitting only unidirectional fluid flow therethrough, and a motion-transmitting element extending from said foot member through said cylinder to said movable piston and responsive to the rocking of said foot member for reciprocating said movable piston in said cylinder.

3. A fluid-cushioned artificial leg comprising a leg member, a foot member pivotally attached to said leg member for rocking motion relatively thereto, a fluid cylinder mounted in one of said members and having an outer cylinder bore therein, a hollow movable piston reciprocably mounted in said outer cylinder bore and having an inner cylinder bore therein, a stationary piston fixedly mounted in said inner cylinder bore, said stationary piston having a forward fluid passageway and a return fluid passageway therethrough, a one-way valve disposed in each of said passage-

ways permitting only unidirectional fluid flow therethrough, and a motion-transmitting element extending from said foot member through said cylinder to said movable piston and responsive to the rocking of said foot member for reciprocating said movable piston in said cylinder.

4. A fluid-cushioned artificial leg comprising a leg member, a foot member pivotally attached to said leg member for rocking motion relatively thereto, a fluid cylinder mounted in one of said members and having an outer cylinder bore therein, a hollow movable piston reciprocably mounted in said outer cylinder bore and having an inner cylinder bore therein, a stationary piston fixedly mounted in said inner cylinder bore, said stationary piston having a forward fluid passageway and a return fluid passageway therethrough, a one-way valve disposed in each of said passageways permitting only unidirectional fluid flow therethrough, a resilient element engaging and yieldingly urging one of said valves into its closed position, and a motion-transmitting element extending from said foot member through said cylinder to said movable piston and responsive to the rocking of said foot member for reciprocating said movable piston in said cylinder.

5. A fluid-cushioned artificial leg comprising a leg member, a foot member pivotally attached to said leg member for rocking motion relatively thereto, a fluid cylinder mounted in one of said members and having an outer cylinder bore therein, a hollow movable piston reciprocably mounted in said outer cylinder bore and having an inner cylinder bore therein, a stationary piston fixedly mounted in said inner cylinder bore, said stationary piston having a restricted forward fluid passageway and a return fluid passageway therethrough, and a motion-transmitting element extending from said foot member through said cylinder to said movable piston and responsive to the rocking of said foot member for reciprocating said movable piston in said cylinder, and a resilient member yieldingly engaging and urging said piston against said motion-transmitting element.

6. A fluid-cushioned artificial leg comprising a leg member, a foot member pivotally attached to said leg member for rocking motion relatively thereto, a fluid cylinder mounted in one of said members and having an outer cylinder bore therein, a hollow movable piston reciprocably mounted in said outer cylinder bore and having an inner cylinder bore therein, a stationary piston fixedly mounted in said inner cylinder bore, said stationary piston having a forward fluid passageway and a return fluid passageway therethrough, a one-way valve disposed in one of said passageways permitting only unidirectional fluid flow therethrough, a motion-transmitting element extending from said foot member through said cylinder to said movable piston and responsive to the rocking of said foot member for reciprocating said movable piston in said cylinder, and a resilient member yieldingly engaging and urging said piston against said motion-transmitting element.

7. A fluid-cushioned artificial leg comprising a leg member, a foot member pivotally attached to said leg member for rocking motion relatively thereto, a fluid cylinder mounted in one of said members and having an outer cylinder bore therein, a hollow movable piston reciprocably mounted in said outer cylinder bore and having an inner cylinder bore therein, a stationary piston fixedly mounted in said inner cylinder bore, said stationary piston having a forward fluid passageway

way and a return fluid passageway therethrough, a one-way valve disposed in each of said passageways permitting only unidirectional fluid flow therethrough, a motion-transmitting element extending from said foot member through said cylinder to said movable piston and responsive to the rocking of said foot member for reciprocating said movable piston in said cylinder, and a resilient member yieldingly engaging and urging said piston against said motion-transmitting element.

8. A fluid-cushioned artificial leg comprising a leg member, a foot member pivotally attached to said leg member for rocking motion relatively thereto, a fluid cylinder mounted in one of said members and having an outer cylinder bore therein, a hollow movable piston reciprocably mounted in said outer cylinder bore and having an inner

cylinder bore therein, a stationary piston fixedly mounted in said inner cylinder bore, said stationary piston having a forward fluid passageway and a return fluid passageway therethrough, a one-way valve disposed in each of said passageways permitting only unidirectional fluid flow therethrough, a resilient element engaging and yieldingly urging one of said valves into its closed position, a motion-transmitting element extending from said foot member through said cylinder to said movable piston and responsive to the rocking of said foot member for reciprocating said movable piston in said cylinder, and a resilient member yieldingly engaging and urging said piston against said motion-transmitting element.

JOHN HALLER.
